UNITED STATES PATENT OFFICE.

T. J. W. ROBERTSON, OF NEW YORK, N. Y.

MACHINE FOR CUTTING, POLISHING, DRESSING, AND ORNAMENTING GLASS.

Specification forming part of Letters Patent No. 43,042, dated June 7, 1864.

To all whom it may concern:

Be it known that I, T. J. W. ROBERTSON, of the city, county, and State of New York, have invented certain new and useful Improvements in Machinery for Cutting, Polishing, Dressing, and Ornamenting Glass and Vitreous Substances; and I do hereby declare that the following is a full, clear, and exact description of the same, reference being had to the accompanying drawings, forming part of this specification, in which—

Figure 1, Sheet 1, is a front view of my invention, with part of the frame removed. Fig. 2, Sheet 1, is a side view of the lower parts. Fig. 3, Sheet 1, is a plan of that part of the machine below the red line *a a*, Fig. 1. Figs. 4, 5, and 6, Sheet 1, are enlarged views of various parts, which will be described herein-after. Figs. 7 and 8, Sheet 2, are a side view and plan showing the method of operating on several objects at once by one attendant. Figs. 9 and 10, Sheet 2, are front and side views of a modification of the machine shown in the previous figures, and intended to work on flat surfaces.

Similar letters of reference indicate corresponding parts in each of the several figures on the two sheets.

The ornamentation of the surfaces of glass, stone, and kindred substances has heretofore been almost exclusively executed by hand-labor. The globe, goblet, or vessel which the glass-cutter desires to ornament is held in the two hands of the workman, who presses the article against a revolving stone or metallic cutting wheel, and thus, line by line, figure by figure, executes upon the surface of the article whatever ornamentation may be desired. In this manner the workman may configure or carve the glass or other material with wreaths, vines, crests, coats of arms, initials, and various pictures; but only a single article at a time can be operated upon by the workman, and the process is consequently slow and expensive. In other branches of the art the workman operates by means of diamond-pointed hand-tools or by gravers and chisels.

The object of this invention is to dispense with the necessity of hard-labor for ornamenting glass and other substances, and to substitute mechanism in lieu thereof; also to execute the work in a quicker, better, and

cheaper manner than it has heretofore been done.

The nature of my improvement is such that several articles—for example, globes, vases, goblets, or vessels—may be operated upon simultaneously by a single attendant, who may execute upon all of them any mental design that he may desire; or he may follow and execute upon the glass any specified design, drawing, writing, or figuring, which has been previously drawn upon paper, or otherwise conveniently prepared for him. The particular form of the glass is immaterial to the successful operation of my invention. It may be flat, like window-glass, or cylindrical, oval, angular, or any other form.

To enable others skilled in the art to which my invention appertains to make and use my machinery, I will proceed to describe its construction and operation.

A A A represent the main frame of the machine, the highest part having the forked lever B pivoted to it by the pin C. The forked end of this lever gives vertical motion and support to the perpendicular shaft D, which has upon its upper extremity an adjustable collar, E. This collar rests upon the forked end of lever B. The shaft D has two bearings, F F', in the frame of the machine, and is connected by a universal joint, G, to another shaft, H, which has its bearing at F' in a vibrating frame, I, which at its upper end is pivoted to the main frame at F' in such a manner that it may vibrate and also allow the shaft to vibrate in the direction shown in red outline in Fig. 1. On the lower end of this shaft H there is a chuck, J, having jaws K K, to hold the glass goblet or other article to be operated upon.

L is a gear-wheel placed upon the shaft D, said wheel having attached to it two standards, b b', which unite at their upper ends with a cross arm, M, which is also placed upon the shaft D.

N is another horizontal arm, which is also placed upon the shaft D, and is adjustable thereon by the screw c. The outer end of this arm is forked, and is fitted to the standard b so as to allow it to slide up and down with shaft D. The arm N causes the said shaft D, when it revolves, to carry the wheel L with it.

Upon the shaft B, but arranged beneath the gear-wheel L, there is a segment of a wheel, O, having bevel-teeth cut on it. Attached to the lower side of this segment there is a spring, z, and attached to the spring, near its center, there is a vertical pin which passes upward through O into a hole in the rim of L. This pin serves to lock the wheel L and segment O together, and on withdrawing the pin the position of the segment-teeth in respect to the wheel L may be adjusted at will. The segment O gears with another segment, P, which is attached to one end of the sleeve Q. To the other end of this sleeve there is fastened, by the screw d, a forked piece, R, to which is pivoted, at the extremity of the fork e, a two-armed lever, S. In the lower arm of this lever there is a sliding pointer, T, which slides freely up and down it. The upper arm of this lever is connected to one end of the sliding rod U by the link V.

W is a standard rising from the frame of the machine, and forming a bearing for the elbow-lever X. One arm of this lever is connected to the forked lever B by the link Y. This link can be adjusted in any position along the two levers B X by the holes f f f and sliding collar g, to which the link Y is pivoted, so as to vary the amount of vertical motion imparted to the shafts D H from the lever S.

Z is a weight to counterbalance the weight of the shafts D H and their appendages, and also to keep the perpendicular arm of the elbow-lever X in contact with the end of the sliding rod U.

The object of the parts so far described is for transferring any motion given to the pointer T to the glass or other object held in the chuck J. It will be seen, on examining the drawings, that any motion imparted to the pointer T from right to left, or vice versa, as shown in red outline in Fig. 1, will give a vertical motion to the shafts D H, while any motion given to the pointer at right angles to this will give them a partial rotary motion, so that when the pointer is moved the object or article held in the chuck J will have a movement imparted to it, which will be either vertical or rotary, or the rotary and vertical movements will be simultaneously combined, according to the movement given to the pointer by the attendant.

The device for cutting or engraving consists of a wheel, h, on the shaft i, which runs on bearings in the arms j j, which are attached to the revolving sleeve k, which has its bearings in the frame A of the machine. (These parts can be seen best in Fig. 4, Sheet 1, where they are shown enlarged.) To the other end of the sleeve k there is attached a gear-wheel, l, which gears with another wheel, m, on the end of shaft n. On the other end of this shaft there is a bevel-gear-wheel, o, which gears with another bevel-wheel, p, on the lower end of the shaft q, to which is attached the handle r. The sleeve

k forms a bearing for the shaft s, having on one end the fast and loose pulleys t u and on the other end the dish-shaped bevel gear-wheel v, which gears with the bevel-pinion w, communicating motion to the cutting-wheel h. The gear-wheel v is made dish-shaped, as shown in Fig. 4, to allow the cutting-wheel h to be made larger than the pinion, otherwise the pinion would come in contact with the object to be engraved or ornamented. On the under side of the table or platform A' is a small elbow-lever, B', having one arm connected by the pitman C' to the treadle D', and the other arm is pivoted to the shipper E', which swings on this arm and the link G', as shown in red outline in Fig. 1. The spring H', attached to the table, draws the treadle upward, and, acting by means of the pitman C', elbow-lever B', and shipper E', always keeps the belt L' upon the loose pulley t, excepting when the treadle is depressed by the operator, which movement causes the shipper E to move the belt L' onto the fast pulley u, and withdrawing the end of the shipper from the pin Z on the lower end of the vibrating frame I allows the action of the spring I' to bring the glass in contact with the cutting-wheel h. The spring I' draws or presses the glass against the cutter with a yielding pressure, which allows the glass, if its surface is irregular, to move back and forth in accordance with such irregularities, and thus, while constantly keeping the glass against the cutter, it (the spring) prevents the glass from being broken or too deeply or unevenly cut.

The operation of the machine may be described as follows: The article to be ornamented is inserted in the chuck J, and fastened by the screws. The operator then takes hold of the pointer T with one hand and the handle r with the other, and presses his foot on the treadle D', causing the shipper E' to move in the direction shown in red outline, which movement slips the driving-belt L' from the loose pulley t to the fast pulley u, and at the same time allowing the article that is to be operated on to come in contact with the cutting-wheel h. As soon as the cutting-wheel commences to revolve, the operator makes the pointer T follow the groove x in the pattern y, thus, as before described, giving a motion to the glass exactly corresponding to the grooved design on the pattern y, but very much reduced both in length and depth; and as the cutting-wheel is in operation during this time it has cut a design corresponding to the motion of the glass. It is obvious that the attendant may execute any mental design upon the glass simply by moving the pointer, so that the presence of a drawing or a pattern, as shown at y, is not essential; but to secure uniformity of work, where large numbers of a given pattern are to be cut, and also to assist the unskilled workman, a pattern is desirable. As soon as the pointer T has passed over all the lines in the design

the operator should lift his foot off the treadle D' , allowing the reaction of the spring H' to ship the belt L' onto the loose pulley t , so as to stop the motion of the cutting-wheel h , and move the glass away from it.

On examining the figure or design thus produced it will be found to occupy but one-eighth of the circumference of the glass. If the design is intended to run completely around the glass, the operator should depress the spring z under the segment O low enough to withdraw the pin J' out of the hole K' it then occupies, and then turn the wheel L until another hole comes around, into which the spring returns the pin J' , connecting the wheel and segment together again, so that one cannot move without the other. The operator then proceeds as before, making another portion of the wreath, and repeats these operations until the design is finished, when the glass is removed from the chuck and another one inserted in its place to be operated on, as before described.

Instead of covering only one-eighth of the circumference of the glass, the design on the pattern may be so proportioned as to cover one-sixth, one quarter, or any other portion desired.

If the work to be done on the machine is of the finest class, the operator should so turn the handle r as to keep the shaft of the cutting-wheel at right angles to the line of the design; it is at that time cutting, always changing the position of the cutting-wheel as the line of the design changes. This makes sharper lines and better work generally than would be the case if the wheel h were always held in one position.

In some kinds of work, where the change of direction of the lines to be cut is very sudden, as in turning a sharp corner, or in lines crossing each other, it is advisable to stop the machine before changing the position of the cutting-wheel h ; but when the change is small or gradual, as in making a curve or circle, the change in the position of the cutting-wheel can be made without stopping its motion.

If sharpness of outline is not required in the design, the work can be executed much faster by simply fixing the cutter in one position by any convenient means, and then guiding the glass by the pointer T , without reference to the position of the cutting-wheel; or an addition to the machinery may be made by which the pointer T and the parts controlling the position of the cutting-wheel h may be so connected that the pointer T will always keep the cutting-wheel running in the direction of the line it is making.

In some kinds of work it might be convenient to have the spring I' connected with a treadle in such a way that the operator could, by pressing on the treadle, vary the power of the spring I' so as to press the glass upon the wheel with a light or heavy pressure.

Figs. 7 and 8, Sheet 2, show the machinery

adapted to work on three or more objects at once, controlled and guided by one operator. In this form parts of three machines, like that shown in Sheet 1, are combined and connected together, as shown, so that all the parts controlling the three objects to be ornamented are moved and guided by one pointer T and lever S , in the following manner: The lifting end of the lever B is made with three or more arms, as shown in the plan, Fig. 8, Sheet 2, instead of one arm, as in the machine first described. Each of these arms acts on a separate shaft, $D D D$, moving them all alike. Each of these shafts has a gear-wheel, L , carrying the standards $b b'$, and is fitted up and made in all respects exactly the same as the shafts $D H$ in the separate machine, with the exception of the segments $O P$. These wheels all gear together and have the same amount of motion, and will give the same motion to each of the shafts, and the objects held in the chucks at the bottoms of those shafts, as to the central one, which is guided by the pointer T , with the exception that the two outside shafts and appendages turn in a direction contrary to the one in the center. This will cause the pattern to run in one direction on the center glass and in the opposite on the outside ones. This might be objectionable in some cases, especially in engraving letters, and could be remedied by inserting an intermediate pinion between the gear-wheels, which would cause them all to turn precisely alike. The gearing controlling the position of the cutting-wheels should all be connected in the same manner.

Although the machine is shown only in triplicate in the drawing in Sheet 2, yet it is obvious that it might be made to operate on four, five, or six glasses at once, or even more, on the same principle.

Figs. 9 and 10, Sheet 2, show a modification of this machine, applicable to the ornamentation of flat surfaces. The parts for giving motion to and controlling the position of the cutting-wheel are the same as for cylindrical surfaces, as also are the parts for giving motion to the object that is to be ornamented, excepting that portion below the universal joint G , connecting the two shafts $D H$. The vibrating frame I is extended so as to form two vertical guide-rods, $M' M'$, which are connected at the bottom by the brace N' . On these guide-rods are the bearings $O' O'$ of a carriage, P' , having horizontal guide-rods $Q' Q'$, on which slides the bed R' , to which is fastened the glass S' , by the clamps $T' T'$ and screws $U' U'$. The shaft H is connected to the carriage P' by means of the stud V' , having a pointed screw, W' , which enters into a V-shaped groove in the shaft, so as to allow the shaft H to turn in the stud V' , and yet be capable of moving the carriage up and down. On the end of the shaft H there is a pinion, X' , which takes into a rack, Y' , on the bed.

It will be seen from this description and an

examination of the drawings that the carriage P' moves vertically with the shaft H , thus giving the bed R' , carrying the glass S' , a corresponding motion, and the pinion X' , acting on the rack Y' , gives the bed a sideward motion, both motions being governed by the operator moving the pointer T according to the pattern or design that he wishes to execute.

This invention may be also applied to the cutting and polishing of glass and other substances. In this case it would be best to have an even number of machines connected together, (in the manner hereinbefore described for triplicate cutting,) all being controlled by one operator, and using one-half of the machines for cutting, and the remainder for polishing the figures after they are cut, so that the cutting and polishing may both go on at the same time.

In engraving, cutting, or polishing glass the necessary grinding mixtures of emery and water or oil, or polishing materials—such as tripoli, pumice-stone, putty-powder, &c.—should be supplied to the wheel h in the usual manner; or they may be applied to the glass itself, instead of to the cutting-wheel.

In etching glass with acid this machine may be very usefully employed by removing the cutting-wheel and substituting therefor an etching-needle, which should be fastened in the shaft s in such a manner that the point will project as far forward as the cutting-wheel does.

The process of etching with such a machine would be as follows: Having coated the glass with etching-wax, grease, or any substance that will resist the action of the acid, it is fastened in the machine, and the operator moves the pointer T , by which the glass is correspondingly moved against the etching-needle according to the design on the pattern. The glass is then removed from the machine and submitted to the fumes of hydrofluoric acid, which eats into or corrodes the glass in all places where the wax or grease has been removed by the needle.

Metallic and other objects may be etched in the same manner by using the appropriate acids.

Ornamental coloring matter or liquids or pencil designs may be applied to the surfaces of various other articles and substances by substituting a conducting-tube, pencil, or brush in place of the cutting-wheel.

Machines constructed substantially on the plans herein shown may be used for the cutting and ornamentation of the surfaces of various substances. For marble or stone work the machine would not require much change, except to make it larger and stronger; but for most other purposes the wheel h , which acts by abrasion, should be removed and replaced by one that has cutters and is otherwise suited to the particular work then in hand.

I do not mean to limit myself to the exact

forms of mechanism here shown and described, as the principle of my invention may be embodied in various styles to suit the different kinds of work to be done. One example of a very obvious change would be to place the cutting-wheel upon the glass-holder H , or its equivalent device, and to give to the cutting-wheel those changes of motion and position, under the control of a guiding-lever, S , as are here given to the glass holder, the glass itself occupying substantially the position now given to the cutter. The changes of form in the parts and in the location of the driving-pulleys, belts, &c., necessary to accommodate the glass and cutter to such variations in their arrangements in respect to each other, will readily suggest themselves to any skillful mechanician, and therefore do not require to be here detailed.

Having thus described my invention, what I claim as new in the art of cutting, polishing, dressing, and ornamenting vitreous substances, and desire to secure by Letters Patent, is—

1. The construction of the shaft or holder H , which carries the glass, so that it will vibrate to and from the cutter or polisher, substantially as and for the purpose herein shown and described.
2. The pressing of the glass with a yielding pressure against the cutter or polisher, substantially as herein shown and described.
3. The combination of the vibrating frame I with the glass-holder H , substantially as herein shown and described.
4. The combination of the spring-treadle and belt-shipper with the glass-holder H and cutter h , substantially as herein shown and described.
5. Imparting a vertical or a lateral movement, or a combined vertical and lateral movement, to the glass or other article to be ornamented, substantially as herein shown and described.
6. The combination of a governing lever or pointer, S , which is subject to the will of the operator, and a glass-holder which obeys the pointer, substantially as herein shown and described.
7. The combination of the wheel L , arm N , and shaft D , substantially as herein shown and described.
8. The combination of the adjustable segment O with the wheel L and shaft D , substantially as herein shown and described.
9. The combination of the shaft D and segment O with the segment P and lever S , in the manner herein shown and described.
10. The combination of the shaft D , lever B , elbow-lever X , and rod U with the lever S , substantially in the manner herein shown and described.
11. The combination of the lever S with the fork R , sleeve Q , and rod U in the manner substantially as herein shown and described.
12. The arrangement of the cutter or pol-

isher so that the position of its axis may be changed or varied in correspondence with the changes or curvatures of the lines of the design, substantially as herein shown and described.

13. The employment of adjusting mechanism between the lever S and the glass-holder or

the cutter for the purpose of enlarging or diminishing, at will, the dimensions of the ornament or figure to be executed upon the glass.

T. J. W. ROBERTSON.
